FRANKLYN B. HALE, OF SAN FRANCISCO, CALIFORNIA, ASSIGNOR OF ONE-HALF TO
WILLIAM C. BRUMFIELD, OF SAN FRANCISCO, CALIFORNIA

MEANS AND METHOD OF FIXING ELECTRODES IN GLASS TUBES

Application filed November 27, 1928. Serial No. 322,109.

My invention has for its object the means and method of mounting an electric conductor or electrode in the walls of a glass tube and particularly a glass tube which is vacuumized or filled with rarefied gas or gases and through which an electrical discharge is intended to be maintained; whereby any excessive heat generated by the electrode is dissipated and reduces the temperature differences between that portion of the electrode or conductor within the tube and the glass seal of the tube itself to prevent cracking or other destructive effects that heretofore have developed such heat differences.

Other objects will appear from the drawing and specifications which follow:

These objects I attain by mounting the electrode upon a conducting wire and advancing the conducting wire a material distance within the tube beyond the sealed joint between the conductor and the tube and also mounting on said inner portion of the conductor a heat conducting body in contact with the conductor adjacent to the electrode and within the tube and adapted to convey and dissipate the heat proceeding from the electrode towards the seal in the tube and therefore to by-pass the heat from the said conductor and tube seal.

By referring to the accompanying drawing my invention will be made clear:

In the drawing Fig. 1 is a section of one end portion of a vacuum tube which may be of any form, and in which an electric discharge is adapted to be maintained and showing in detail my invention applied thereto and employing a different form of electrode from that of the other figures.

Fig. 2 is a side view of a tube to which my invention is applied.

Fig. 3 is one form of an electrode with its conductor as first prepared.

Fig. 4 is the electrode and conductor of Fig. 3 to which the heat dissipating member has been applied, prior to introduction in the tube.

Throughout the figures similar numerals refer to identical parts.

Numeral 1 indicates a conventional glass tube adapted to contain rarefied gases and

within which an electric discharge may be maintained between the electrodes 2 and 3, the emerging current being conveyed thereto by the conductors 4, 5 respectively.

At 6 is shown a thimble of glass or other heat conductive dielectric material having a heat dissipating surface and body portion between the seal 7 embracing the conductor 5 and the seal 8 of the glass tube 1 and embracing the conductor 5.

During the electric discharge from the electrode 3, the latter becomes quite hot and materially hotter than the glass wall 1 and the metallic conductor 5.

The vacuum in 10 provides a fairly good heat insulator and therefore unless other means be provided, excess heat is conducted from the electrode 3 heating the conductor 5 more highly than the glass portion of the tube embracing the conductor at the seal 8.

Although it is well recognized practice to provide the conductor 5 of material having approximately the same heat expansion coefficient as the glass, the difference in temperature above recited is frequently sufficient to cause a greater expansion on the body portion of the conductor 5 than in the glass when the electrode is being brought up to its temperature, or a materially less temperature than the glass tube 1, after the current has been cut off due to the more rapid dissipation of heat from the conductor 5 than from the glass.

In both cases this temperature difference is apt to crack the glass around seal 8 and destroy the vacuum. To reduce this temperature difference between the conductor 5 and the seal 8, I provide a dielectric member 6 which may be with advantage, as here shown, formed as a glass thimble, sealed at 7 to the conductor 5, and spaced at 11 from the said conductor and preferably contacting as at 12 with the outer portions of the glass seal 8.

Heat from the electrode 3 is then diverted at 7 as it advances along the conductor 5, and is partly dissipated from the surface 6 and is also conducted to the outer portions of the seal 8 at 12, so that the entire seal 8 is more evenly heated while the temperature of the conductor adjacent the seal 8, is propor-

tionally reduced, that is the temperature difference between the glass of the seal 8 immediately adjacent the conductor 5 and the conductor 5 is greatly reduced.

5 This reduction in temperature differences effected by the means 6 prevents cracking or damage of the seal at 8 and maintains more perfectly vacuum at 10, within the tube 1.

10 Conversely after the current has been cut off, the cooling of the conductor 5 within the tube would be slower by the cooling of the seal 8 because of the rapid dissipation of heat from the seal 8, whereas when my invention is employed the conductor within the tube is 15 cooled by the member 6 and the outer portions of the seal 8 are retained relatively warmer so that the entire body of the seal 8 reduces in temperature more nearly at the same rate as the conductor 5.

20 It will now be seen that by my invention the entire body of the seal 8 is retained more nearly at the temperature of the conductor 5 where it passes through the seal 8 during the heating and during the cooling and during 25 variations in the energization of the tube 1.

Reference is herein made to my copending application Serial No. 322,108 filed November 27, 1929, wherein is claimed certain matter herein disclosed.

30 I claim:

1. In combination with an electrode sealed in a tube and having a conducting stem, a separate member of heat conducting material within said tube positioned about said stem and spaced therefrom and a seal between said stem and said member adjacent the electrode.

2. In combination with an electrode sealed in a tube and having a conducting stem, a glass thimble positioned about said stem and spaced therefrom and a seal between said stem and said thimble adjacent the electrode.

3. In a luminescent gas tube the combination set forth in claim 1 wherein one end of said member is in physical contact with a portion of said tube.

4. In a luminescent gas tube the combination set forth in claim 2 wherein one end of said thimble is in physical contact with a portion of said tube.

5. The method of reducing the heat transfer from an electrode having a stem to a sealed portion positioned between a glass tube and said stem which consists of mounting a heat conductor spaced about said stem within said tube one end of said conductor sealed to said stem adjacent the electrode and the other end in physical contact with said sealed portion between the glass tube and the conductor remote from said conductor.

6. The method of producing a luminescent gas tube with an electrode mounted on a stem which consists of sealing a heat conductor of greater internal diameter than said stem to said stem adjacent said electrode then sealing

said stem in said tube with said conductor in physical contact with a portion of said tube adjacent said last named seal.

7. The method of producing a luminescent gas tube with an electrode mounted on a stem which consists of sealing a heat conductor of greater internal diameter than said stem to said stem adjacent said electrode, then sealing said stem in said tube with said conductor in physical contact with a portion of said tube adjacent said seal, then exhausting said tube and then introducing a small quantity of an inert gas adapted to exhibit luminescence upon an electric discharge from said electrode.

80 FRANKLYN B. HALE.
